TABLE LAMP OR SIMILAR ARTICLE

Matthew Gennaro, Bronx, N. Y., assignor to I. J. Scharf
Co., Inc., Bronx, N. Y., a corporation of New York

Application July 11, 1958, Serial No. 51,738

Term of patent 14 years

(Cl. D48—20)

Fig. 1 is a side perspective view of a table lamp, showing my new design.

Fig. 2 is a top plan view thereof.

The bottom of the figured portion of the lamp base is substantially the same as the top except for the contrast.

I claim:

The ornamental design for a table lamp or similar article, substantially as shown and described.
